UNITED STATES PATENT OFFICE.

WILLIAM H. HOYT, OF STAMFORD, CONNECTICUT.

HOLLOW WARE.

SPECIFICATION forming part of Letters Patent No. 339,419, dated April 6, 1886.

Application filed November 11, 1885. Serial No. 182,503. (No model.)

To all whom it may concern:

Be it known that I, WILLIAM H. HOYT, of Stamford, in the county of Fairfield and State of Connecticut, have invented certain new and 5 useful Improvements in Hollow Ware, of which the following is a full, clear, and exact description.

My invention consists of ornamental hollow ware—such, for example, as vases, jars, boxes, &c.—made in whole or in part of the pith of cornstalks.

Reference is to be had to the accompanying drawings, forming part of this specification, in which similar letters of reference indicate corresponding parts in both the figures.

Figure 1 is a perspective view of a circular jar made of pith. Fig. 2 is a perspective of an angular box made of the same material.

The circular vessel A is made of the pith of 20 cornstalks cut into small curved blocks *a* and connected together with glue or other adhesive material. The square box B (shown in Fig. 2) is made of flat, square, or brick-shaped pieces

of pith cemented edge to edge and joined at the corner. The bottom B' may be of paste- 25 board, wood, or other material, or it may be made of pith, as desired.

I am aware of the fact that hollow ware has been contrived of coiled rattan, of paper reinforced with vulcanized water-proof material, 30 and of pressed paper strengthened by layers of cloth or veneer, and of the further fact of the preparation for general use in the arts of the pith of cornstalks.

Having thus described my invention, what I 35 claim as new, and desire to secure by Letters Patent, is—

As a new article of manufacture, hollow ware made of the pith of cornstalks, the latter being in the form of blocks joined or connected 40 together, substantially as set forth.

WILLIAM H. HOYT.
